UNITED STATES PATENT OFFICE.

JOHN SHERIDAN, OF NEW YORK, N. Y.

LAUNDRY APPLIANCE.

1,196,305.

Specification of Letters Patent. Patented Aug. 29, 1916.

Appliance filed October 11, 1915. Serial No. 55,215.

To all whom it may concern:

Be it known that I, JOHN SHERIDAN, a citizen of the United States, residing at 198 Seventh avenue, in the city and county of New York and State of New York, have invented new and useful Improvements in Laundry Appliances, of which the following is a specification.

This invention relates to improvements in laundry appliances, particularly for domestic purposes, and to the types used in hand scrubbing washable textile articles, known as washboards.

The objects of the invention are, first, to provide a wash-board in which a bar or cake of laundry soap is so arranged as to make intimate contact with the articles as they are rubbed over the surface of the board, the soap being moved forward as it becomes worn.

A second object is to provide a receptacle within the frame of the wash-board adapted to contain laundry accessories, as bluing, etc. And finally to provide a device of this character of unusually cheap and strong construction, and attractive appearance.

These objects are attained by the novel construction and combination of parts hereinafter described and shown in the accompanying drawings, forming part of this specification, and in which:

Figure 1 is a front elevation of a wash-board made in accordance with the invention. Fig. 2 is a vertical sectional view, taken on line 2—2 of Fig. 1, and Fig. 3 is a transverse sectional view taken on line 3—3 of Fig. 1.

The drawing shows the wash-board, having sides 10, the lower end of which may enter a tub or the like containing water, suds and the article to be washed; a cross tie 11 connects the upper ends of the side frames, which are further braced by a cross bar 12 secured rigidly between the sides.

Extending from the upper tie 11 to the bar 12, and filling the space between the sides, is a central metallic plate 13, corrugated from side to side and constituting the usual rubbing surface.

At about the center of the plate an opening is made through which extends the side of a bar of soap 15, the soap being guided by the inturned edges 16 of the metal plate and supported by a backing plate 17 provided with spurs 18 which enter the soap 55 preventing it from being displaced.

Arms 19 extend laterally from the plate 17, the arms being so formed as to clear the sides 10, and passing through openings in the ends are screws 20, having enlarged ends 21, 60 the screws being threaded into nuts 22 set on the sides 10 and operated by the knobs 23 which extend through the side frames where they are easily accessible for operation in turning and thereby bringing the soap into 65 register with the face of the board.

At the upper end of the wash-board, adjacent to one of the frame sides is a pocket or chamber 25, adapted to contain a bottle or stick of bluing 26, the same being held 70 therein by the slide 27, thus forming a very convenient and appropriate receptacle for a material almost invariably used in laundry work.

Having thus described my invention and 75 explained its construction and use, what I claim as new and desire to secure by Letters Patent, is:—

In a wash board, the combination with a frame having longitudinal side members, a 80 corrugated scrub plate carried by said frame and having an opening through the center thereof adapted to receive a bar of soap, a single resilient support for the soap aligned with said opening, rods engaged with the 85 ends of said resilient support, said rods being screw-threaded their entire length and extended through said frames above the surface thereof, and means for the separate operation of said rods whereby the surface of 90 the soap may be adjusted parallel with the surface of said scrub plate.

In testimony whereof, I have signed my name to this specification.

JOHN SHERIDAN.
